UPPER PIVOT FOR VENTILATOR PANELS

Guy M. Lane and Harold G. Thunder, Detroit,
Mich., assignors to Motor Products Corporation,
Detroit, Mich., a corporation of New York

Application September 8, 1947, Serial No. 772,744

5 Claims. (Cl. 296—44)

1

This invention relates to window assemblies of the type adapted for installation on vehicle bodies.

More particularly the invention concerns itself with vehicle body ventilator window assemblies of the type having a frame and having a ventilator supported in the frame for swinging movement about a generally vertical axis.

One of the objects of this invention is to improve generally ventilator window assemblies of the above type by providing a pivotal mounting composed of a relatively few simple parts capable of being inexpensively manufactured and installed.

Another object of this invention is to provide a pivotal connection which is neat in appearance and is of such a design as to enable readily installing the ventilator in the window frame.

The foregoing as well as other objects will be made more apparent as this description proceeds, especially when considered in connection with the accompanying drawing, wherein:

Figure 1 is a fragmentary perspective view of a window assembly embodying the features of this invention;

Figure 2 is a sectional view through the hinge provided between the top of the ventilator frame and the window frame;

Figure 3 is a perspective view of one of the hinge brackets;

Figure 4 is a fragmentary perspective view of the ventilator frame showing the cooperating hinge bracket; and

Figure 5 is a plan view, partly in section, of a part of the ventilator frame showing the manner in which the hinge bracket in Figure 4 is assembled.

Referring now more in detail to the drawing, it will be noted that the numeral 10 designates a vehicle body window assembly comprising a window frame 11, a garnish molding 12 surrounding the frame 11 and a ventilator 13. The window frame 11 is channel-shaped in cross section and a seal 14 is secured in the channel of the frame. The seal 14 is of the conventional type shaped to weather-seal the joint between the ventilator 13 and window frame 11 in the closed position of the former.

The ventilator embodies an inwardly opening channel-shaped frame 15 and a panel 16 having the marginal edges thereof secured in the channel of the frame 15 in accordance with conventional practice. The ventilator is supported in the window frame 11 for swinging movement about an up and down axis indicated in Figure 1 of the drawing by the broken line 17 and located inter-

2

mediate the front and rear edges of the panel 16. The ventilator is held in any one of a number of angular positions of adjustment about the axis 17 by a friction pivot 18 connecting the bottom bar of the ventilator frame 15 to the adjacent bar of the window frame 11. The friction pivot 18 forms no part of the present invention, and accordingly, is not shown in detail herein.

The top bar of the ventilator frame 15 is pivotally connected to the top bar of the window frame 11 by a hinge 19 comprising a pair of brackets 20 and 21. The bracket 20 is of a design which enables the same to be readily formed from sheet metal, and is fashioned with a laterally extending attaching flange 21' adapted to be secured to the base of the top bar of the window frame 11 by rivets 22. The body or depending portion of the bracket 20 is fashioned to form a tubular pin or pindle 23 adapted to assume a position with its axis coincident with the axis 17 about which the ventilator panel 16 swings. In this connection it will be noted from Figure 3 of the drawings that the slots 24 in the attaching flange 21' of the bracket for receiving the rivets 22 are elongated to enable limited adjustment of the bracket 20 during assembly to insure positioning the pindle 23 in axial alignment with the axis 17.

The bracket 21 is also of a nature which enables the same to be readily formed from a sheet metal stamping. The bracket 21 comprises an attaching flange 26 and a body portion which is twisted at an angle to the attaching flange and is curled to form a sleeve 27 of sufficient internal diameter to freely receive the lower end of the pindle 23. The attaching flange 26 is adapted to be secured to the inner surface of the base of the channel-shaped frame 15 by rivets 29 and the inner side flange of the frame 15 is formed with an elongated slot 30 for receiving the flange 26. In the preferred construction the slot 30 has a length somewhat less than the attaching flange 26, and the latter is inserted through the slot at an angle 45 in the manner indicated by the broken lines in Figure 5 of the drawing. This construction improves the appearance of the assembly since it renders the slot practically unnoticeable.

As indicated above, the bracket 21 is twisted 50 intermediate the ends to locate the sleeve portion 27 with its axis aligned with the axis of the pindle 23. Thus during assembly the desired hinge connection is established by merely telescoping the sleeve portion 27 over the lower end of the pindle 23.

What we claim as our invention is:

1. A window assembly comprising a window frame, a ventilator supported in the window frame for swinging movement about an up and down axis, a frame for the ventilator having a channel-shaped frame member opening inwardly with respect to the window opening and having an opening in one side wall of the frame member, a bracket having an attaching flange extending into the channel of the frame member through said opening and having a part positioned to one side of the frame member in concentric relation to the axis of swinging movement of the ventilator, means for securing the attaching flange to the base of the channel-shaped frame member, and means secured to the window frame and pivotally engageable with the part aforesaid of the bracket.

2. A window assembly comprising a window frame, a ventilator supported in the window frame for swinging movement about an up and down axis, a frame for the ventilator having a channel-shaped frame member opening inwardly with respect to the window opening and having an opening in one side wall of the frame member, a bracket having an attaching flange extending into the channel of the frame member through said opening and having a tubular portion positioned to one side of the frame member in concentric relation to the axis of swinging movement of the ventilator, means for securing the attaching flange to the base of the channel-shaped frame member, and a pintle engageable in the tubular portion and secured to the window frame.

3. A window assembly comprising a window frame, a ventilator panel supported in the window frame for swinging movement about an up and down axis, a frame for the ventilator panel having a channel-shaped frame member opening inwardly with respect to the window opening for receiving the adjacent edge of the panel and having an opening in one side wall of the frame member, a one-piece bracket having an attaching portion extending through said opening into the channel of the frame member and having a portion looped to provide a sleeve having its axis coincident with the axis of swinging movement of the

ventilator, means for securing the attaching portion of the bracket to the base of the channel-shaped frame member, and a pintle having one end secured to the window frame and having the opposite end engageable in said sleeve.

5. A window assembly comprising a window frame, a ventilator panel supported in the window frame for swinging movement about an up and down axis, a frame for the ventilator panel having a channel-shaped frame member opening inwardly with respect to the window opening for receiving the adjacent edge of the panel and having an opening in one side wall of the frame member, a one piece bracket having an attaching portion extending through said opening into the channel of the frame member and having a portion looped to provide a sleeve having its axis coincident with the axis of swinging movement of the ventilator, means for securing the attaching portion of the bracket to the base of the channel shaped frame member, a second one-piece bracket having a portion secured to the window frame and having a portion forming a pintle engageable in said sleeve.

20 6. A window assembly comprising a window frame having a top frame bar, a ventilator panel supported in the window frame for swinging movement about an up and down axis, a frame for the ventilator panel having a channel-shaped frame member at the top opening inwardly with respect to the window opening for receiving the upper edge of the ventilator panel, a sheet metal one-piece bracket having an attaching flange insertable into the channel of the top ventilator frame member through a slot in one side wall of the latter and having a tubular part positioned to one side of the frame member in concentric relation to the axis of swinging movement of the ventilator, means for securing the attaching flange to the base of the channel-shaped member, and a second bracket secured to the top frame bar of the window frame and having a pintle extending downwardly through the tubular portion of the first bracket.
